PRINTING TELEGRAPH APPARATUS

Raymond E. Zenner, Brookfield, Ill., assignor to
Teletype Corporation, Chicago, Ill., a corpora-
tion of Delaware

Application October 23, 1939, Serial No. 300,692

17 Claims. (Cl. 178—17)

The present invention pertains to printing telegraph apparatus and more particularly to such apparatus capable of tabulation recording.

In printing telegraph systems employing recording apparatus provided with tabulating mechanism, time is necessarily required to move the type carriage or platen carriage, as the case may be, from one position to another during tabulation. In manual operation of key-controlled recording apparatus, cognizance is taken of the tabulating time by the operator, who, during such time, refrains from further operation of the keyboard. However, in automatic operation of such recording apparatus, by means of tape transmitters wherein the apparatus is unattended for extended periods of time, it is desirable to simulate manual control during tabulation so as to suspend transmission automatically during the time that the carriage is in motion while tabulating, thus preventing the improper operation of the recording apparatus.

The primary object of the present invention is to provide a transmitting means for automatically controlling telegraphically the recordation of information containing tabular operations.

Another object of the invention is to provide in a telegraph transmitter utilizing a signal control strip, a timing device controlled by said strip in accordance with a predetermined signaling condition.

A feature of the invention resides in associating a permutation code device with the tape sensing levers of a tape transmitting distributor, which device controls a screw and follower timing device which, in turn, controls a contact in the circuit of the start magnet of said distributor.

The present invention provides for the operative association of a tape transmitter with a receiving printer equipped with a tabulating mechanism, whereby the receiving printer in preparing tabulated matter is made to respond to the operation of a transmitter which automatically takes cognizance of tabulating time in accordance with the perforations in the tape. Such an arrangement produces a printed copy containing tabular matter corresponding to the perforations in the tape.

Specifically, when a perforated record is made which involves tabulated portions, it is expedient to compensate for the tabulation time required at the recorder by suspending transmission during tabulation. As in the type of tabulating recorder disclosed in U. S. Patent 2,076,864, a tabulator bar extends across the front of the

10 machine, is carried by brackets mounted in the typing unit, and is capable of swinging toward and away from the type carriage. The tabulator bar carries a number of adjustable tabulation stop members which determine the positions to which the type carriage is automatically propelled (a distance equivalent to a plurality of character spaces) following the reception of a tabulator code signal combination.

15 In the tape transmitter according to the present invention for suspending transmission during tabulation time intervals, the series of tape sensing levers have associated therewith a corresponding series of permutation code bars which, in accordance with the permuted arrangement thereof, effects the selection of any one of three selectable bars in response to the "letters" (lower case), "figures" (upper case), and tabulating signals. Specifically, when the tape sensing levers assume positions in accordance with the perforations in the tape, a restoring bail recedes, permitting another series of levers, intermediate said sensing levers and said permutation code bars, to engage or pass projections on said sensing levers, depending upon the position of each sensing lever (that is, in accordance with whether or not the sensing levers have found or sensed a hole in the tape). Said intermediate levers, in turn, are articulated to and position the permutation code bars, which are coded, for the present purpose, to permit the selection of the three selectable bars, identified with the "letters," "figures," and tabulator code signals.

20 In response to a "letters," "figures," or tabulator signal, one of these bars will be selected, whereupon an operating bail will engage a shoulder on the selected bar and impart movement thereto. The three selectable bars control the follower arm of a screw and follower timing device which, in turn, controls a contact included in the circuit of the start magnet of the transmitting distributor. When the tabulator signal is received, the permutation code bars are set correspondingly and the selectable bar allotted to the tabulator code signal is selected and operated to lift the follower arm away from the worm or screw. This permits the follower arm to be moved by spring tension away from the contact (which is in the transmitting distributor start magnet circuit) so that this contact opens, releasing a start magnet of the transmitting distributor and stopping transmission upon completion of the tabulator signal. At the close of the signal cycle, the follower arm is permitted to engage the continuously rotating worm which

then feeds the follower back against the tension of its spring, to close said contact, thereby causing transmission to be resumed. The length of the interruption is determined by the length, pitch and/or speed of the worm, and may be made adjustable by providing an adjustable stop to control the distance through which the follower is moved away from the contact by its spring.

A better understanding of the present invention may be had from the following description taken in conjunction with the accompanying drawing wherein like reference characters are used to designate similar parts throughout the several views, and wherein.

Fig. 1 is a schematic diagram of the arrangement according to the present invention;

Fig. 2 is a transverse cross-sectional view of the tape transmitter according to the present invention;

Fig. 3 is a sectional view taken substantially on line 3—3 of Fig. 2;

Fig. 4 is a fragmental plan view of the tape transmitter according to the present invention with parts broken away to show mechanism essential to the invention;

Fig. 5 is a sectional view taken on line 5—5 of Fig. 3;

Fig. 6 is an enlarged sectional view taken on line 6—6 of Fig. 3; and

Fig. 7 is a view taken on line 7—7 of Fig. 6.

Fig. 8 is a modification of a portion of the invention.

In Fig. 1 there is shown at 15 the front elevational view of the principal part of a receiving printer of the type disclosed in U. S. Patent 1,904,164, showing the application thereto of the tabulating mechanism of the type shown in U. S. Patent 2,076,864, supplemented with a schematic circuit diagram showing a tape transmitter and a plurality of receivers in the same line circuit. The tape transmitter 11 is shown diagrammatically as connected in a signal line 10, in which are also connected line magnets 12, 13, and 14 of receiving printers 15, 16, and 17. Although only the printer 15 will be described, it is understood, of course, that the printers 16 and 17 are of identical construction. The tape transmitter, indicated generally as 11 in Fig. 1, comprises a series of tape controlled contacts 18 (a five-unit code transmitter being shown in the present embodiment), and a commutator distributor 19.

As indicated by the wiring diagram in Fig. 1, the five tongues on the tape transmitter 11 move between upper and lower contacts 18, called the "spacing" and "marking" contacts, respectively. The perforations in the tape determine which contact tongues will be on spacing contacts and which on the marking contacts. As the brush arm 21 of the commutator distributor 19 revolves, it will successively connect through the brush carried thereby the five segments to the line, each in turn sending out a marking or spacing impulse, depending upon the permutative setting of the contacts 18 in accordance with the perforations in the tape. The revolution of brush arm 21 is controlled by a stop magnet 22, the armature 23 of which co-operates with the extremity of brush arm 21. In the energizing circuit for magnet 22 is a battery 24 and a contact 25. The operation of contact 25 is controlled by the screw and follower timing device shown in Fig. 5 in a manner to be described. When the stop magnet 22 is de-energized upon the opening of contact 25, the armature 23 will be spring biased to a position to arrest the brush arm 21. On the other

hand, when the contacts 25 are closed, magnet 22 will be energized and armature 23 will be attracted, thus freeing the brush arm 21 for rotation. As is well-known, when the armature 23 is released it arrests the contact brush arm 21 on the stop segment of the distributor 19. The signals thus generated at the transmitter 11 are transmitted over the signal line 10 to the receiving stations, whereat these signals operate the receiving magnets 12, 13, and 14 to control the operation of their respective selector mechanisms.

Briefly, the printing apparatus, to which the tabulating mechanism (with which the present invention is concerned) is applied, comprises a 15 typing unit (shown generally as 15) which includes a primary selecting mechanism, indicated generally by the receiving electromagnet 12, which is of the type disclosed in U. S. Patent 1,745,633 (and also fully disclosed in Patent 1,904,164), and a secondary selector or selector vane assembly, indicated generally as 26. The selector vane assembly 26 controls, through a series of bell crank levers 27, a corresponding series of curved code bars 28 carried in a movable type carriage, indicated generally as 29. As set forth in Patent 1,904,164, this type carriage 29 is movable longitudinally with respect to a stationary platen (not shown). During normal printing operations, the carriage 29 is movable rightwardly (as viewed in Fig. 1) along rails 31 in a step-by-step manner indicative of character spacing. As disclosed in U. S. Patent 2,076,864, continuous spacing may be effected upon receipt of a code signal identified as the tabulating code signal which functions to initiate the operation of the tabulating mechanism.

The mechanically operated tabulating arrangement, according to the present embodiment of the invention, comprises a tabulator bar 32 extending across and in front of the typing unit 15. Bar 32 is provided with depending portions 33 and 34 through which it is pivotally mounted on bracket 35 carried on the printer frame. Thus, tabulator bar 32 is adapted to be swingable toward and away from the carriage 29. Bar 32 is provided with a longitudinal slot 36 extending substantially the entire length of the bar. In this slot are carried a plurality of adjustably positionable tabulation stop members 37, which are adapted to be clamped to the bar 32. Stop members 37 are each provided with inclined or cam portions conformed to co-operate with a cam striker 38 carried by the type carriage 29 to terminate the tabulating operation. The tabulator bar 32 is also provided with a depending arm 39 adopted to co-operate in latching manner with the front end of a tabulator control lever 41, controlled by the tabulator function lever 42, as described in Patent No. 2,076,864. Thus, when the tabulator function lever 42 is selected for operation upon the proper setting of selector vanes 26, it is drawn toward the vane 26 by its spring, and in so doing it acts to rotate lever 41 to lower its front end into latching engagement with arm 39, thus permitting spring 43 to pull tabulator bar 32 toward the printer 15 (away from the observer, as viewed in Fig. 1). This action presents tabulation stops 37 into the path of stroker 38. The rear end of lever 41 raises and thus lifts the rear space pawl from the spacing ratchet (not shown), thereby freeing said ratchet for continuous rotation to effect corresponding rotation of the spacing worm (not shown), thus causing the type carriage 29 to move quickly and smoothly toward the right until the striker 38 cams the first tabulation stop 37, that it encounters in its path, out-

wardly (or toward the observer), thereby rocking tabulator bar 32 to effect the disengagement of lever 41 from arm 39, which action restores the rear spacing pawl into engagement with the spacing ratchet to terminate the spacing operation and arrest the movement of the type carriage 29.

Now, during the tabulation operation just described, transmission of signals from the transmitter 11 must be stopped and remain so during the tabulation time interval. To achieve this result, the transmitter 11 is provided with a tape controlled timing arrangement which suppresses transmission for a period of time to assure the completion of the longest tabulation time interval.

The tape transmitter 11 (Figs. 2, 3 and 4) comprises a base portion 44 on which is supported a tape sensing means or record reader indicated generally as 45, a commutator distributor indicated generally as 49, and a motor 46. The record reader 45 comprises a bracket 47. Pivotally carried on a shaft 48 mounted in said bracket is a series of tape sensing levers 49. Levers 49 (five in number in the present embodiment) are normally spring biased in a counterclockwise direction by individual springs 51. Depending arms 52 of levers 49 co-operate with the upper arm of a bail lever member 53. Bail 53 is pivotally supported at 54 by bracket 47. The lower arm of bail 53 co-operates with the head of a screw 55 adjustably carried at one end of a bail operating lever 56 pivoted at 51 to the base 44. The opposite end of lever 56 carries a cam follower roller 58 which co-operates with a cam 59 fixed to the lower end of the vertically positioned commutator distributor shaft 61 suitably journaled in the base 44.

Each of the levers 49 also carries at the extremity of its arm 62 a contact spring 63 provided with contact points to co-operate with the respective marking and spacing contacts 18 insulatably mounted in bracket 47. Projecting rightwardly from each of the depending arms 52 (as viewed in Fig. 2) is an arm 64 which is provided near its outer extremity with an upstanding portion 65, and carried on portion 65 is a tape sensing pin 66. The pins 66, as is well-known, feel the lower side of the tape 67 for perforations therein, and if a perforation is found, the pin 66 passes through the perforation and the lever 49 assumes the counterclockwise position shown in Fig. 2. On the other hand, if a perforation is not found, the pin 66 bears against the lower side of the tape 67 and the lever 49 assumes its clockwise position. The springs 63 carrying the contact points assume corresponding positions with relation to the marking and spacing contacts 18.

As is also known, the tape 67 is provided with tape feed holes which co-operate with tape feed pins 68 of a tape feed roller or sprocket fixed to a shaft 69 to which is also secured a tape feed ratchet 71 which co-operates with a tape feed pawl 72, which is carried at the extremity of a lever similar to levers 49 and are controlled by bail 53. This practice being well-known, the structure therefor is not indicated in Fig. 2.

Co-operating with the outer extremities of arms 64 of levers 49 is a corresponding series of levers 73 pivotally carried at 14 by bracket 47. Levers 73 are normally biased counterclockwise by individual springs 75. A bail member 76 co-operates with the upper arms of levers 73 and is pivoted at 77 to the base 44. Bail 76 is also

5 provided with a heel portion 78 which co-operates with the lower or downwardly directed arm of the bail member 53. Bail 76 is normally biased counterclockwise by a spring 79. Thus, when the bail member 53 is operated upon by lever 56 to be rotated in a counterclockwise direction, all of the levers 49 will be rotated clockwise by the action of the upwardly extending portion of the bail 53 with the depending arms 52 of levers 49. In this manner all of the pins 66 are withdrawn from the tape 67 preparatory to sensing a new line or transverse row of perforations.

10 As bail 53 is thus rotated counterclockwise, its 15 downwardly projecting arm acts upon the heel 58 of bail 76 to rotate it clockwise against the action of its spring 79 about the pivot 77. Bail 76 thus acts upon the upwardly projecting arms 20 of levers 73 to withdraw them from co-operative relation with the ends or extremities of the arms 25 64 of levers 49. It is observed that clearance is provided between the upper extremities of levers 73 and the ends of arms 64 of levers 49, so that as levers 49 are rotated clockwise by bail 53, the levers 73 will have been withdrawn by bail 76 under the action of bail 53 in sufficient time to escape the ends of said arms 64. Alternatively, clearance can be provided between arms 30 52 and bail 53, instead of between the upper extremities of levers 73 and the ends of arms 64 of levers 49, in which event, levers 73 will be withdrawn from beneath the ends of arms 64 before bail 53 operates on arms 52 to withdraw pins 66 from the holes in the tape 67. Incidentally, the tape feed pawl operating lever (not shown) is also actuated clockwise by bail 53 so as to lower the pawl 72 sufficiently to engage a succeeding tooth on ratchet 67, so that when bail 53 is again permitted to rotate clockwise 35 due to the pull or tension of springs 51 on levers 49, a corresponding spring on the tape feeding levers acts to raise the pawl 72 to rotate the ratchet 71, and hence feed sprocket wheel 68, to 40 advance the tape 67 a distance of one transverse row. Counterclockwise rotation of levers 49 under the action of their springs 51 in proper timed relation to the tape feed operation, will bring the pins 66 into co-operative relation with the tape 67, those levers 49 rotating further counterclockwise whose pins 66 have found a perforation 45 in the tape. Those levers 49 whose pins 66 have found a perforation in the tape will be rotated sufficiently so that the extremity of its arms 64 will clear the upper end of lever 73 associated therewith. On the other hand, those levers 49 50 whose pins 66 have not encountered a perforation in the tape 67 will not be rotated sufficiently and their arms 64 will not clear the upper end of lever 73. Thus, when the bail 76, under the action of spring 79, is rotated counterclockwise at the proper time in the cycle of operation, levers 73 under the action of their individual springs 75 will also be rotated counterclockwise, those levers 73 being rotated a greater distance whose upper end is free of the extremity of arm 64 of its associated lever 49. The remaining of levers 55 73 will not be rotated the full counterclockwise distance, but will be blocked by the ends of the arms 64 of their associated levers 49.

60 The lower extremities of the five levers 73 are 65 pivotally articulated to a corresponding series of five code bars 81, which are slidably supported on rods 82 and 83 suitably mounted in the base 44. Thus, the setting imparted to levers 73

under the control of levers 48 is transferred to the code bars 81. Although not shown, a detent could readily be provided to preserve the setting of the code bars 81 until reset by levers 78.

There are associated with code bars 81 three selector members 84, 85 and 86 which are selected in response to the "figures" or shift code signal, the tabulator code signal, and the "letters" or unshift code signal, respectively. Accordingly, the code bars 81 are so notched or coded that when an alignment of notches occurs in response to the "figures" or shift signal, the bar 84 will be selected. If an alignment of notches occurs in response to the tabulation signal the bar 85 will be selected, as shown in Fig. 2. If an alignment of notches occurs in the code bars 81 in response to the "letters" or unshift signal, the bar 86 will be selected.

Bars 84 and 86 are slidably carried on a support 87 (Figs. 3 and 7) suitably positioned within the base portion 44. Bar 85 is pivotally connected to an arm 88 pivotally mounted on a pivot shaft 89 which is suitably journaled in the base portion 44. Bars 84, 85 and 86 are normally urged leftwardly (as viewed in Fig. 3) by individual springs 91. Individual springs 92 serve to urge bars 84, 85 and 86 upwardly into selective relation with the code bars 81. A lever 93 is rockably carried on pivot shaft 89, and its leftwardly extending arm terminates in a bail portion 84 which acts to withdraw bars 84, 85, 86 from selective engagement with code bars 81 to permit a resetting of said code bars. Lever 93 also carries at the extremity of its rightwardly extending arm a follower roller 95 which cooperates with a ball operating cam 96 fixed to a shaft 97 suitably mounted in the base portion 44. Rotation is imparted to shaft 97 through the instrumentality of a gear 98 (Fig. 4) fixed thereto, which gear is meshed with a gear 99 fixed to the shaft 81. Also fixed to shaft 97 is a cam 101 which cooperates with a cam follower roller 102 carried at the extremity of one arm of an operating ball lever 103 pivoted at 104. Integral with lever 103 is a bail portion 105 which co-operates with V-shaped shoulders 106 (Figs. 3 and 7) on the bars 84, 85, and 86. When any of the bars 84, 85 or 86 is selected, shoulder 106 is presented into the path of bail 105, which, when the lever 103 is rocked counterclockwise by the cam 101 the selected one of bars 84, 85 and 86 is actuated rightwardly (as viewed in Fig. 3) against the action of its individual spring 91. The V-shaped conformation of shoulder 106 and the corresponding conformation of the co-operating edge of bail 105 affords an interlock between bail 105 and the selected bar 84, 85 or 86, during the cycle of operation of ball 105.

Lever 88 is part of a timing device controlled by the bar 85. Having reference to Figs. 3 and 5, the lever 88 has pivotally connected thereto a screw follower lever 107. At the extremity of lever 107 there is provided a screw follower pin 108 adapted to engage the thread of the screw or worm 109. Screw 109 is fixed to a shaft 111 to which is also fixed a gear 112 (Fig. 4) which is adapted to mesh with a gear 113 fixed to an auxiliary shaft 114 disposed vertically and parallel to shaft 81. It is understood that shafts 111 and 114 are appropriately journaled in the base portion 44. Fixed to the upper end of vertical shaft 114 is a gear 115 which meshes with a gear 116 frictionally connected to shaft 81. Gear 116 meshes with a worm or pinion 117 fixed to the armature shaft 118 of the motor 46. It

is observed that gear 116 is constantly rotating and, accordingly, through gears 112, 113 and 115, fixed to shafts 111 and 114, constant rotation is imparted to the screw 109.

When the screw follower pin 108 is engaged with the thread on the screw 109, lever 107 is constantly urged toward the right thereby (as viewed in Fig. 5) against the tension of a spring 119 to hold the contact 25 closed. As previously mentioned, contact 25 is connected in the circuit of the magnet 22. Therefore, so long as contact 25 remains closed, the brush arm 21 of the commutator distributor 19 is constantly rotating due to the fact that the circuit for the stop magnet 27 is closed, thereby energizing said stop magnet, thus attracting the armature 23 against the action of its retractile spring 121 (Fig. 4). Armature 23 being held in its attracted position against the stop 122 its arm 123 is held or maintained out of the path of stop lug 124 integral with stop disc 125 fixed to the shaft 81.

Under certain operating conditions to be presently described, bar 85, when selected, is actuated by ball 105 rightwardly to impart clockwise rotation to lever 88 (as viewed in Fig. 3), which movement acts to withdraw the screw follower pin 108 from the thread of the screw 109, whereupon spring 119 acts upon lever 107 to swing it in a counterclockwise direction, as viewed in Fig. 5, against a suitable stop (not shown) but which is positioned so as to align the pin 108 with the opposite end of the thread with which it is shown engaged in Fig. 5. Contact 25 is thereupon permitted to open, the effect of which is to cause the de-energization of magnet 22, thus permitting the retractile spring 121 to rock the armature lever 123 counterclockwise to bring the arm 123 thereof into the path of stop lug 124 of stop disc 125. When this occurs, shaft 81 and all elements fixed thereto cease to rotate due to the friction clutch 126 between gear 115 and shaft 81. Thus, shaft 81 is caused to be stopped with the brush arm 21 engaging the stop segment of the distributor 19.

As previously mentioned, the selector bar 85 is effective only under certain operating conditions; namely, that condition established in response to an upper case character signal assigned to the tabulation function. To assure that the bar 85 is operated only in response to the upper case character signal, "figures" and "letters" shift bars 84 and 86 are provided. As is well known in five-unit code systems, a five-unit code signal represents not only a character in the upper case but also a character in the lower case, and to distinguish between these two characters, said character code signals are preceded by a "figures" shift code signal or a "letters" unshift code signal.

Since in the present embodiment the tabulator bar 85 is effective only in response to a code signal in the upper case, means is provided to distinguish between upper and lower case character signals. To achieve this result, bars 84 and 86 are provided which co-operate with a member 127, Figs. 3, 6 and 7. As previously described, bar 85 is pivoted to lever 88. Bars 84 and 86 are pivoted to individual brackets 87. As viewed in Fig. 6, member 127 is carried on a shaft 128 which is suitably mounted in the base 44. Member 127 is adapted to be clamped to a portion 129 of base 44 by means of a spring washer 131 (Fig. 6) in a manner to hold member 127 into any position to which it has been rocked. Member 127 is provided with a depending portion 132

terminating in a laterally disposed stud portion 133 adapted to engage a slot 134 (Fig. 7) in bar 86. As viewed in Fig. 7 member 127 is also provided with a leftwardly directed portion 135 of arcuate conformation. As viewed in Fig. 6, the portion 135 is stepped so that the part confronting bar 85 is lower than that portion confronting bar 84. Bar 84 is provided with a hump or cam portion 136 which co-operates, as will presently appear, with portion 135 of member 127.

Member 127 is operated by bars 84 and 86 to permit or prevent the selective operation of bar 85 in the following manner. In Figs. 3 and 7, it is understood that the bars 84, 85 and 86 are shown in their leftward position, whereat they are held by their individual springs 91. Now, when it is desired to suspend transmission during tabulation, the "figures" or shift signal precedes the tabulator signal, in which event the tape sensing levers 49 will be set in accordance with the "figures" or shift signal, which setting through the instrumentality of levers 73 will be transferred to code bars 81, thus producing an alignment of notches above the bar 84, which, when permitted by bail 94 to rise, will rise into said alignment of notches to bring its shoulder 106 into the path of bail 105 which, when operated by cam 101, will urge bar 84 rightwardly against the tension of its spring 91, thus causing cam portion 136 to act upon portion 135 to rock the member 127 in a clockwise direction, as viewed in Fig. 7, thus bringing the pin 133 to the left end of the slot 134 in bar 86 and providing a clearance between bar 85 and member 135 sufficient to permit bar 85 to be selected subsequently by the bars 81 in response to the tabulator code signal. Then, when the tape 67 has been stepped one step, the levers 49 are operated to sense the new transverse row of perforations just presented thereto to control through the levers 73 the setting of the code bars 81, which will produce a new alignment of notches above the bar 85, so that when the bar 85 is permitted to rise by the bail 94, it will rise into the notches thereabove, this selection being permitted because of the prior raising of the portion 135 (Figs. 6 and 7) sufficiently to permit this selection. Then, when bail 105 is operated, it co-operates with shoulder 106 on the selected bar 85 to urge the bar 85 rightwardly to release, through lever 88, follower pin 108 from the threads of the screw 109, thus permitting contact 25 to open, as previously described, to cause the de-energization of stop magnet 22 and the stoppage of rotation of shaft 61.

Upon the release of follower pin 108 from the threads of screw 109, spring 119, as previously described, acts to rotate lever 107 to its extreme left-hand position, as viewed in Fig. 5. Follower pin 108 will again engage the threads of screw 109, which rotates continuously and as it rotates follower pin 108 will move from left to right, as viewed in Fig. 5. When it reaches its extreme right-hand position or the position shown in Fig. 5, contacts 25 will be closed and an energizing circuit for stop magnet 22 will be completed. The armature 23 will be attracted free of the brush arm 21 which thereupon will rotate by power communicated thereto from motor 46 through the friction clutch. As brush arm 21 rotates, transmission to the line conductor will be resumed and will continue until contacts 25 are again opened through the operation of the mechanism previously described. Particularly significant with regard to the arrestment of the

brush arm 21 is the fact that the period of arrestment represents the longest period which the movable carriage requires to move from one stop position to the next possible stop position, which, of course, will vary in accordance with the tabular matter being composed.

When it is desired to prevent the selection of bar 85, even though there is an alignment of notches in the code bars 81 to permit its selection, the "letters" or unshift code signal is employed to cause, through levers 49 and 73, the setting of the code bars 81 to produce an alignment of notches above the bar 86, which, when permitted by bail 94, rises into the notches to bring the shoulder 106 thereon into the path of bail 105, which, when operated, causes bar 86 to be actuated rightwardly. It will be remembered that since pin 133 (Fig. 7) is at this time at the left end of slot 134, member 127 will be actuated in a counterclockwise direction, thus lowering portion 135 substantially into contact with bar 85. Since the clamping effect of spring washer 131 is greater than the tension of spring 92, member 127 will remain in its counterclockwise position (as shown in Fig. 7) until again actuated in an opposite direction by the cam portion 136 of bar 84. The purpose of blocking bar 85 after "letters" code combination, but permitting its selection after "figures" code combination, is to effect the printing of a character having the same code combination as the tabulator code combination (which is characteristic of the Baudot code) without interruption of transmission in the "letters" condition, and operation of the tabulator function, with interruption of transmission in the "figures" condition.

Modification

In Fig. 8 is shown a modified arrangement for controlling the blocking of the bar 85, in which the pivoted member 141 is substituted for the member 127 of the principal form of the invention. The member 141 is pivotally supported at 142 to the base 44 at a point substantially above bar 85. At each end, the member 141 is pivotally articulated to bars 84 and 86, through the instrumentality of pivot studs or pins 143 and 144 integral with bars 84 and 86, respectively. Member 141 is also provided with a projecting portion or arm 145 having a laterally disposed end 146 adapted to overlie the bar 85.

Like member 127, member 141 in Fig. 8 is operated by bars 84 and 86 to permit or prevent the selective operation of bar 85 in the following manner. In Fig. 8 it is understood that the bars 84, 85, and 86 are shown in their leftward position, whereat they are held by their individual springs 91. Now, when it is desired to suspend transmission during tabulation, the "figures" or shift signal precedes the tabulator signal, and a setting will occur in code bars 81 to effect the selection of bar 84, which, when permitted by bail 94 to rise, will bring its shoulder 106 into the path of bail 105 which, when operated by cam 101, will urge bar 84 rightwardly against the tension of its spring 91, thus causing through pin 143, the rotation of member 141 in a clockwise direction about its pivot 142 to swing lateral end 146 out of the path of bar 85 to permit bar 85 to be selected subsequently by the code bars 81 in response to the tabulator code signal. Then, when bar 85 is selected, it will rise under the control of bail 94 into the aligned notches thereabove in code bars 81, this selection being permitted because of the prior swinging of end 146

away therefrom to permit this selection. Thus, when ball 105 is operated it co-operates with shoulder 108 on the selected bar 88 to urge the bar 88 rightwardly to release, through lever 88, the follower pin 108 from the threads of the screw 109, thus permitting contact 28 to open, as previously described, to cause the deenergization of stop magnet 22 and the stoppage of rotation of shaft 61.

When it is desired to prevent the selection of bar 88, the "letters" or unshift code signal is employed to cause the setting of the code bars 81 to produce an alignment of notches above the bar 88, which, when permitted by ball 84 rises into the notches to bring the shoulder 108 thereon into the path of ball 105, which, when operated, causes bar 88 to be actuated rightwardly. It will be remembered that since the pin 144 is at this time at the right end of its respective slot in member 141, member 141 will be rotated in a 20 counterclockwise direction about pivot 142, thus swinging end 146 into a blocking position directly above bar 88. Incidentally, if the springs 81 for bars 84 and 88 are dispensed with, the slots in member 141 associated with pins 143 and 144 can be omitted. In this event, either of the bars 25 84 or 88 will be held in their operated positions, under the control of a spring washer at pivot 142, until returned by the operation of the other bar, in well-known manner.

While the present invention has been explained and illustrated in contemplation of a specific embodiment, it should be understood that numerous modifications and variations may be made without departing from the spirit or scope thereof. It is, therefore, intended not to be limited to any of the illustrative details of the accompanying drawings, nor to the specific language employed in the foregoing specification, but to be permitted instead a latitude of interpretation as indicated by the hereunto appended claims.

What is claimed is:

1. In combination, a recorder responsive to code signals, a transmitting apparatus comprising a tape sensing means, a distributor having a definite rest position, periodically operated means in said recorder responsive to a characteristic code signal, and timing means controlled by said tape sensing means to control the arrest of said distributor in its rest position for the duration of operation of said periodically operated means.

2. In combination, a recorder responsive to code signals, a transmitting apparatus comprising a tape sensing means, a distributor having a definite rest position, periodically operated means in said recorder responsive to a characteristic code signal, and screw and follower timing means controlled by said tape sensing means to control the arrest of said distributor in its rest position for the duration of operation of said periodically operated means.

3. In combination, a recorder responsive to code signals, a transmitting apparatus comprising a tape sensing means, a distributor having a definite rest position, permutation code mechanism controlled by said sensing means, periodically operated means in said recorder responsive to a characteristic code signal, and timing means controlled by said permutation code mechanism in response to said sensing means to control the arrest of said distributor in its rest position for the duration of operation of said periodically operated means.

4. In combination, a recorder responsive to code signals, a transmitting apparatus comprising a tape sensing means, a distributor having a definite rest position, permutation code mechanism controlled by said sensing means, means to transfer the selective condition of said sensing means to said mechanism, periodically operated means in said recorder responsive to a characteristic code signal, and a timing means controlled by said mechanism in accordance with a certain transferred selective condition to control the arrest of said distributor in its rest position for the duration of operation of said periodically operated means.

5. In combination, a recorder responsive to code signals, a transmitting apparatus comprising a tape sensing means, a distributor having a definite rest position, permutation code mechanism controlled by said sensing means, means to transfer the selective condition of said sensing means to said mechanism, periodically operated means in said recorder responsive to a characteristic code signal, a timing device, and means controlled by said permutation code mechanism in accordance with a certain transferred selective condition to govern the operation of said timing device to control the arrest of said distributor in its rest position for the duration of operation of said periodically operated means.

6. In combination, a recorder responsive to code signals, a transmitting apparatus comprising a tape sensing means, a distributor having a definite rest position, permutation code mechanism controlled by said sensing means, periodically operated means in said recorder responsive to a characteristic code signal, a timing device, and means controlled by said permutation code mechanism and effective under certain selective conditions to govern the operation of said timing device to control the arrest of said distributor in its rest position for the duration of operation of said periodically operated means.

7. In combination, a recorder responsive to code signals, a transmitting apparatus comprising a tape sensing means, a distributor having a definite rest position, permutation code mechanism controlled by said sensing means, periodically operated means in said recorder responsive to a characteristic code signal, a timing device, a member for controlling the effectiveness of said device, and controlling the operability of said member, a pair of other members and an element operated by said pair of members whereby the effectiveness of said timing device to control the arrest of said distributor in its rest position for the duration of operation of said periodically operated means is determined.

8. In a transmitting apparatus, elements for sensing the indicia in a tape, a distributor having a definite rest period, and timing means controlled by said tape sensing elements to control the arrest of said distributor in its rest position for a predetermined period.

9. In a transmitting apparatus, a tape sensing means, a distributor having a definite rest period, and screw and follower timing means controlled by said tape sensing means to control the arrest of said distributor in its rest position for a predetermined period.

10. In a transmitting apparatus, a tape sensing means, a distributor having a definite rest position, permutation code mechanism controlled by said sensing means, and timing means controlled by said permutation code mechanism in response to said sensing means to control the ar-

rest of said distributor in its rest position for a predetermined period.

11. In a transmitting apparatus, a tape sensing means, a distributor having a definite rest position, permutation code mechanism controlled by said sensing means, means to transfer the selective condition of said sensing means to said mechanism, and a timing means controlled by said mechanism in accordance with a certain transferred selective condition to control the arrest of said distributor in its rest position for a predetermined period.

12. In a transmitting apparatus, a tape sensing means, a distributor having a definite rest position, permutation code mechanism controlled by said sensing means, means to transfer the selective condition of said sensing means to said mechanism, a timing device, and means controlled by said permutation code mechanism in accordance with a certain transferred selective condition to govern the operation of said timing device to control the arrest of said distributor in its rest position for a predetermined period.

13. In a transmitting apparatus, a tape sensing means, a distributor having a definite rest position, permutation code mechanism controlled by said sensing means, a timing device, a member for controlling the effectiveness of said device, an element for controlling the operability of said member, and a pair of other members for determining the effectiveness of said element for governing the effectiveness of said timing device to control the arrest of said distributor in its rest position for a predetermined period.

14. In a transmitting apparatus, a tape sensing means, a distributor having a definite rest position, permutation code mechanism controlled by said sensing means, a timing device, a member for controlling the effectiveness of said device, a pivoted element for controlling the operability of said member, and a pair of other members for pivoting said element for governing the effectiveness of said timing device to control the

arrest of said distributor in its rest position for a predetermined period.

15. In combination, a recorder responsive to code signals, a transmitting apparatus comprising a tape sensing means, a distributor having a definite rest position, permutation code mechanism controlled by said sensing means, periodically operated means in said recorder responsive to a characteristic code signal, a timing device, a member for controlling the effectiveness of said device, a pivoted element for controlling the operability of said member, and a pair of other members for determining the effectiveness of said members for governing the effectiveness of said timing device to control the arrest of said distributor in its rest position for the duration of operation of said periodically operated means.

16. In combination, a recorder responsive to code signals, a transmitting apparatus comprising a tape sensing means, a distributor having a definite rest position, permutation code mechanism controlled by said sensing means, means to transfer the selective condition of said sensing means to said mechanism, periodically operated means in said recorder responsive to a characteristic code signal, a timing device, and pivoted means controlled by said permutation code mechanism in accordance with certain transferred selective conditions to govern the effectiveness of said timing device to control the arrest of said distributor in its rest position for the duration of operation of said periodically operated means.

17. In a telegraph transmitter, elements for sensing the indicia in a tape, a distributor having a definite rest period, means for timing the period said distributor is in its rest position, and means controlled by the tape sensing elements for controlling said timing means to effect the arrestment of said distributor and to maintain it in its rest position for a predetermined period of time.

RAYMOND E. ZENNER.
